CLAIM

The ornamental design for a dispenser, as shown and described.

DESCRIPTION

FIG. 1 is an isometric view of the top, front, and right side of the dispenser embodying my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The dash-dash-dash lines are included for the purpose of illustrating portions of the dispenser that form no part of the claimed design. The dash-dot-dash lines are included for the purpose of illustrating boundary lines that form no part of the claimed design.
